UNITED STATES PATENT OFFICE

2,523,273

ENGINE ACTUATED VENTILATING SYSTEM

Charles E. Blundell, Warrington, Fla.

Application October 14, 1946, Serial No. 703,125

6 Claims. (Cl. 98—50)

1

This invention relates to new and useful improvements and refinements in ventilating systems, more specifically, ventilating systems for mine shafts, and the like, and the principal object of the invention is to provide a novel apparatus for efficiently and economically removing foul air from such mines, to insure the safety and well-being of the workers employed therein.

Although the invention may be employed for ventilating purposes in general and for ventilating mine shafts in particular, it is primarily intended for use in association with soft coal mines. The subterranean shafts in such mines are usually filled with explosive natural gas originating from the coal deposits, and the presence of this gas is not only detrimental to safety, but produces harmful effects upon the health of the miners.

It is, therefore, a further object of the invention not only to eliminate the above disadvantages by providing means for withdrawing the explosive gas from the mine shaft, but also to usefully utilize the gas after it has been withdrawn.

Another object of the present invention is to provide a ventilating system which is actuated by an engine already existing in the mine, and which, by this token, can be operated without additional expenditure.

A still further object of the invention is to provide a ventilating system which is simple in construction, safe and dependable in operation, and which does not require particular attention or maintenance.

An additional object of the invention is to provide a ventilating system which is of a portable nature and which is otherwise well adapted for the purpose for which it is intended.

With the above more important objects in view, and such other objects as may become apparent as this specification proceeds, the invention consists essentially of the arrangement and construction of parts as illustrated in the accompanying drawings, in which:

Figure 1 is a perspective view of the invention, the same being partially broken away to reveal its construction, and

Figure 2 is a cross-sectional view, taken substantially in the plane of the line 2—2 in Figure 1.

Like characters of reference are used to designate like parts in the specification and throughout the several views.

Referring now to the accompanying drawings in detail, the invention is shown in association with a soft coal mine, the same including a sub-

2

terranean mine shaft 10 which is accessible from the ground surface 11 through the medium of a substantially vertical air shaft 12.

The mine, of course, usually includes a plurality of the shafts 10, radiating at various levels and in several directions from the vertical shaft 12. However, for purposes of simplicity of illustration, the structure of the mine is not elaborated upon in the accompanying drawings.

10 The mine equipment usually includes an internal combustion engine such as the Diesel engine 13, which is coupled to a suitable electric generator 14 and also actuates an air compressor 15 through the medium of suitable transmission 16. The power from the generator 14 is employed for energizing the lights 17 in the shaft 10 and the air line 18 from the compressor 15 is also available in the shaft for actuating pneumatic hammers, or the like.

20 The structure heretofore described is, of course, well-known in the art, and the essence of the invention resides in the provision of a hermetically sealed chamber 19, disposed preferably above the ground level 11, as will be clearly apparent from the accompanying drawings. To facilitate strength and portability, the chamber 19 is preferably of metallic construction, and the aforementioned engine 13 is positioned in and completely enclosed by the chamber.

30 The crank shaft 20 of the engine 13 projects outwardly from the chamber to drive the aforementioned generator and compressor 14 and 15 respectively, and the exhaust pipe 21 of the engine also extends from the chamber and communicates with the atmosphere.

35 The engine air inlet pipe 22 communicates with the interior of the chamber 19 and a suitable duct 23 extends through the ground and connects the chamber with the mine shaft 10.

40 It will be noted that the lower end of the duct 23 is disposed remotely with respect to the air shaft 12.

45 A short length of pipe 24, hereinafter referred to as an auxiliary air inlet, is provided in the chamber 19 and communicates with the atmosphere. The inlet 24 is equipped with an externally manipulable control valve 25, and the purpose thereof will be more fully hereinafter explained.

50 The wall of the chamber 19 is formed with an inwardly concaved, rupturable depression 26 and with an outwardly convexed rupturable depression 27, the purpose thereof also being herein-after more fully detailed.

55 Finally, the chamber 19 is provided with a

man-hole, hermetically sealed by a door 28, whereby access may be gained into the chamber for the purpose of servicing the engine 13.

Having thus described the construction of the invention, the operation thereof will now be presented.

The engine 13 will, of course, drive the generator 14 and the compressor 15 in the well-known manner, and when the engine is in motion, considerable volume of air will be drawn thereinto through the inlet pipe 22 from the chamber 19, to support the combustion of fuel. However, since the chamber is hermetically sealed, a draft of atmospheric air will be produced downwardly through the air shaft 12, through the mine shaft 10, and upwardly through the duct 23 into the chamber 19, to replace the air in the chamber which has been consumed by the engine. This continual draft or current of air is indicated by the arrows 29 and it will be noted that in this manner, the desired ventilation of the mine shaft will be duly effected.

The products of combustion will be discharged into the atmosphere through the exhaust pipe 21 and it should be particularly noted that explosive natural gases originating from the coal deposits in the shaft 10 will not only be withdrawn from the shaft, but they will be, in effect, admixed with the current of air and delivered to the engine 13, wherein such explosive gases will be usefully utilized as a supplementary source of fuel.

Means are also provided for controlling the rate of ventilation. The same consists of the aforementioned valve equipped auxiliary air inlet 24, which communicates with the atmosphere, as has been already explained. When the valve 25 is closed, the current of air through the duct 23 will represent the entire source of air supply of the engine 13. However, when the valve 25 is open, the air supply of the engine will originate partially from the mine shaft and partially from the atmosphere. Accordingly, by fully closing or regulating the opening of the valve 25, the current of air drawn through the mine shaft may be effectively controlled and the rate or velocity of ventilation correspondingly adjusted.

It should, of course, be realized that the air requirements of a large Diesel engine are considerable and that one engine will amply satisfy the ventilation needs of an extensive mine shaft. Several engines may, of course, be employed for exceptionally large installations.

In order to protect the mine from possible inconvenience or damage in the event that the duct 23 becomes obstructed, the aforementioned depression 26 is formed in the wall of the chamber 19. This depression, by virtue of its concavity offers lesser resistance to atmospheric pressure than the remaining wall structure of the chamber. Accordingly, if the duct 23 becomes obstructed, the air pressure within the chamber 19 will be considerably reduced by the continued operation of the engine 13, and the external atmospheric pressure upon the depressed area 26 will rupture the same, so that the entire air supply of the engine 13 will be drawn directly from the atmosphere.

Another form of pressure responsive means is embodied in the invention, the same becoming operative in the presence of abnormal pressure in the chamber 19, such as may be occasioned by the explosion of the engine 13.

This means consist of the aforementioned convexed depression 27 which is similar to the de-

pression 26, but is disposed on the outer, rather than the inner surface of the chamber wall. In the event of excessive air pressure in the chamber, the depression 27 will be ruptured and the internal pressure will be promptly relieved into the atmosphere, without damaging the chamber 19.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

I claim as my invention:

1. An engine actuated ventilating system, comprising in combination, a hermetically sealed chamber, an internal combustion engine positioned in said chamber, a duct connecting said chamber with the space to be ventilated, an auxiliary air inlet in said chamber communicating with the atmosphere, a control valve provided on said inlet, the entire air supply of said engine being delivered selectively through said duct or partially through said duct and partially through said air inlet, and an inwardly concaved rupturable depression formed in the wall of said chamber, said depression offering lesser resistance to atmospheric pressure and affording external pressure responsive means for delivering the entire air supply of said engine from the atmosphere upon the obstruction of said duct.

2. In combination with a coal mine shaft including an air shaft communicating with the atmosphere, an engine actuated ventilating system, comprising a hermetically sealed chamber disposed above the ground, an internal combustion engine positioned in said chamber, a duct connecting said chamber with said mine shaft at a point remote from said air shaft, an auxiliary air inlet in said chamber communicating with the atmosphere, a control valve provided on said inlet, a supplementary fuel supply of said engine being delivered through said duct, the entire air supply of said engine being delivered selectively through said duct or partially through said duct and partially through said air inlet, and an inwardly concaved, rupturable depression formed in the wall of said chamber, said depression offering lesser resistance to atmospheric pressure and affording external pressure responsive means for delivering the entire air supply of said engine from the atmosphere upon the obstruction of said duct.

3. An engine actuated ventilating system, comprising in combination, a hermetically sealed chamber, an internal combustion engine in said chamber, a duct connecting said chamber with a space to be ventilated, the entire air supply of said engine being delivered through said duct, external pressure responsive means provided on said chamber for delivering the entire air supply of said engine from the atmosphere upon obstruction of said duct, and internal pressure responsive means provided on said chamber for relieving abnormal pressure therein.

4. In combination with a mine shaft communicating with the atmosphere, an engine actuated ventilating system comprising a hermetically sealed chamber disposed above the ground, an in-

ternal combustion engine positioned in said chamber, a duct connecting said chamber with said shaft, the entire air supply and a supplemental fuel supply of said engine being delivered through said duct, external pressure responsive means provided on said chamber for delivering the entire air supply of said engine from the atmosphere upon obstruction of said duct, and internal pressure responsive means provided on said chamber for relieving abnormal pressure therein.

5. The device as defined in claim 1, together with an outwardly convexed rupturable depression formed in the wall of said chamber, said concaved depression affording internal pressure responsive means for relieving abnormal pressure in said chamber.

6. In combination with a soft coal mine shaft including an air shaft communicating with the atmosphere, an engine actuated ventilating system, comprising a hermetically sealed chamber disposed above the ground, an internal combustion engine positioned in said chamber, a duct connecting said chamber with said mine shaft at a point remote from said air shaft, an auxiliary air inlet in said chamber communicating with the atmosphere, a control valve on said inlet, a supplementary fuel supply of said engine being drawn through said duct, the entire air supply of said engine being drawn selectively 30

through said duct or partially through said duct and partially through said air inlet, an inwardly concaved, rupturable depression and an outwardly convexed, rupturable depression formed in the wall of said chamber, said concaved depression offering lesser resistance to atmospheric pressure and affording external pressure responsive means for drawing the entire air supply of said engine from the atmosphere upon the obstruction of said duct, and said convexed depression affording internal pressure responsive means for relieving abnormal pressure in said chamber.
